Inventor:

W. S. Smoot.

United States Patent Office.

W. S. SMOOT, OF WASHINGTON, DISTRICT OF COLUMBIA. #

Letters Patent No. 85,036, dated December 15, 1868.

IMPROVEMENT IN NECK-TIES.

The Schedule referred to in these Letters Patent and making part of the same.

To all whom it may concern:

Be it known that I, W. S. SMOOT, of Washington, in the District of Columbia, have invented a new and improved Neck-Tie; and I do hereby declare the following to be a full clear, and exact description thereof, which will enable those skilled in the art to make and use the same, reference being had to the accompanying drawing, forming part of this specification, in which drawing—

Figure 1 is a front view of my invention, as applied to a collar.

Figure 2 is a transverse section thereof.

Figure 3 is a view of one of the ends of the neck-tie, detached.

Similar letters indicate corresponding parts.

My invention consists of a neck-tie, formed of two parts or ends, each of which is attached to one end of a collar, so that, when the collar is fastened to the shirt-band, the neck-tie ends will overlap one another, take position, and serve the purposes of an ordinary neck-tie.

Heretofore, the ends of the neck-band of a collar have been extended and ornamented, so that, when the collar is secured about the neck, the ends will hang down, and have the appearance of a neck-tie; but, in this construction, it is necessary to button the ends to the neck-band of the shirt, (they being provided with button-holes for this purpose,) thus exposing to view the shirt-button, and preventing the ornamentation of the neck-tie by the addition of a pin or brooch.

In constructing my article, I form the pieces or parts of a tie in a shape corresponding to that shown in fig. 3, they being excised from the material in the modes commonly practised in the manufacture of paper collars, the material being paper, ornamented by painting, printing, or embossing, or by facing it upon either or

both sides with an ornamental fabric, or paper, strengthened by adding to it a woven fabric, either upon its back, or interposed between two thicknesses of it; or I may use a fabric of muslin or silk, strengthened by sizing, as is bookbinders' muslin; or leather may be used with equally good effect.

One of these pieces is attached to each end of a collar, upon the band thereof, at a suitable point from the button-hole, to allow the collar to be attached to the shirt-band, the medium of attachment being either a pin, button, hook, or an adhesive substance.

It will be obvious, by reference to figs. 1 and 2, that when adjusted to the neck, the two parts of the neck-tie overlap, and take the position of the ordinary construction of a tie, in this case, as more fully shown in fig. 2, covering the button of the shirt, and preventing its exposition, this defect having caused the rejection by the public of the old mode of providing collars with an imitation neck-tie.

It is obvious that, by ornamenting both sides of my device, the parts constituting the tie may be reversed, and serve their purpose after having been soiled upon one side; also, that their exposed ends may be varied, in shape or length, to suit the demand of fashion or taste.

Having thus described my invention,

What I claim as new, and desire to secure by Letters Patent, is—

As a new article of manufacture, a neck-tie, consisting of two parts A, formed without button-holes, and adapted to be attached to a collar, substantially as described.

W. S. SMOOT.
